RELEASE DEVICE FOR FLUIDS

Daniel Mapes, Upper Montclair, N. J., assignor
to Walter Kidde & Company, Inc., New York,
N. Y., a corporation of New York

Application November 7, 1931, Serial No. 573,636

10 Claims. (Cl. 169—11)

In another application for Letters Patent of the United States, Serial No. 278,009, filed May 15th, 1928, there is covered a cutter valve designed particularly for the release of carbon dioxide under pressure for the purpose of extinguishing fire, although capable of application for other purposes. In that application a single cutter valve is shown so designed that a plurality of such valves can be operated by fluid pressure 5 from an external source. In the particular embodiment of the invention illustrated in said application, provision is made to discharge the released medium through the same port which permits admission of the actuating fluid so that the 10 released medium may be utilized to assist in actuating the cutter valve of its own container or the cutter valves of other containers operatively connected in the same group. However, with that particular construction the accidental release 15 of the contained medium, as by rupturing of the sealing disc upon the development of excessive pressure within a container, will result in the operation of the cutter valves of the other containers connected in the same group. Furthermore, with such construction, the accidentally released medium is discharged to the same point as the intentionally released medium, which may not only be undesirable, but may be dangerous, because of the unexpected release. 20 It is accordingly an object of the present invention to provide a pressure-operated cutter valve in which the accidental release of the contained medium takes place in a different direction than the intentional release. 25 It is a further object of the invention to provide a pressure-operated cutter valve which is initially operable only by pressure from a designated source of control pressure and in which the accidental release of pressure from any controlled container, as by development of excessive pressure with consequent release of pressure through the container closure, will not cause operation of other cutter valves connected in the same group. 30 A still further object is to provide a system of such pressure-operated cutter valves in which the pressure intentionally released from the controlled containers is added to the pressure from the control container and assists it in actuating the cutter valves. 35

Further objects, not specifically enumerated above, will be apparent as the invention is described in greater detail in connection with the accompanying drawings wherein:

Figure 1 is a view in vertical, central section of a release device or cutter valve in accordance with the present invention.

Figure 2 is a view in elevation showing a plurality of the release devices of Figure 1 and their connections to a battery of containers, the upper ends only of the containers being shown. 5

Figure 3 is a view similar to Figure 1 but showing a different embodiment of the invention.

Figure 4 is also a view similar to Figure 1 but showing a still different embodiment of the invention. 10

In Figure 1 there is shown a portion 1 of a container of carbon dioxide from which the fluid under pressure is discharged through a pipe 2 which is extended in the container nearly to the bottom. To the container is secured one member 3 of a suitable coupling into which the pipe 2 may be threaded, such coupling member being provided at 4 with a seat for a sealing disc 5 and a sealing gasket 6 held in place by a thimble 7. For convenience in manufacture and assembling a second coupling member 8 is formed separately from the coupling member 3 and may be secured thereto by threads 9 engaging cooperating threads 15 on the coupling member 3. A third member 10 of the coupling, also for convenience formed separately, is threaded on the coupling member 8 and is chambered, as at 11, to receive with a close-working fit, as at 12, a piston 13. The coupling member 10 is also chambered above the piston, as at 14, and is provided with a delivery connection, as at 15, through which fluid under pressure may be introduced from a suitable source for the operation of the piston and through which, when 20 the sealing disc 5 is ruptured, the contents of the container 1 may pass for delivery at the point required. 25

Actuated by the piston 13 is a device 16 by which the sealing disc 5 is to be ruptured. In 30 the construction shown this rupturing device is a tubular cutter formed with ports 17 and 18 to permit the fluid from the container 1, when intentionally released, to pass into the chamber 13 and thence through the port 15 into the discharge 35 line 19 which, as shown in Figure 2, is connected with the several valves or release devices of the several containers 1, as by branches 20. In the construction shown the tubular cutter 16 is forced into the piston 13 so as to leave a passage through 40 the piston. It is also shown as bevelled and sharpened at its lower end, as at 21, so that, when driven downward by the movement of the piston 13, it will cut out the disc 5 and allow the fluid 45 to escape from the container 1 into the common 50 discharge line 19. 55

discharge line 19. The piston 13 is shown normally sustained in its highest position by a coiled spring 22.

In order to prevent effective opposition by the fluid released from the respective container or from any other container to the operative movement of the piston 13, the tubular cutter 16 is fitted with a close-working fit within a reduced portion 23 of the coupling 8 between the chamber 11 and the chamber 24 which serves a purpose yet to be described. The chamber 11 is also vented, as at 25, in order to prevent effective opposition to the operative movement of the piston 13 by gas or air within the chamber 11.

15 In order to prevent the contained medium, when accidentally released as by rupturing of the sealing disc 5 under excessive pressure, from being discharged in the same direction in which the intentional discharge takes place and consequently to prevent unintentional operation of the release device of the respective container or of other containers connected in the same group, the ports 17 and 18 of the tubular cutter 16 are arranged with a dividing wall 26 between, the 20 ports 17 normally being in communication with the chamber 24 and the ports 18 normally lying within the reduced portion 23 of the coupling member 8. Upon intentional operation of the piston with consequent downward movement of 25 the hollow cutter 16 to rupture the sealing disc 5, the ports 18 recede within the chamber 24 so that communication is established between the lower and upper portions of the tubular cutter 16 and around the dividing wall 26 through the 30 ports 17, the chamber 24 and the ports 18. The released medium can therefore flow into the chamber 14 and out through the port 15.

In order to permit escape of the medium when accidentally released from its container, the hollow cutter 16 is provided with ports 27 which are normally in alignment with an annular passage 28 which communicates with the atmosphere through passages 29. The accidentally released medium can therefore escape to the atmosphere 45 through the ports 27, the annular passage 28 and the passages 29. However, when the medium is intentionally released, the ports 27 recede within the lower portion 30 of the coupling member 8, thus closing off communication with the atmosphere and preventing the undesired escape of the medium. It will of course be appreciated that the hollow cutter 16 must be conducted with a close-working fit through the portions 30 and 31 of the coupling member 8.

55 It should be noted, in the construction shown in Figure 1, that the seal between the coupling member 8 and the coupling member 3 is produced at the surface 32.

Figure 1 also illustrates a means for effecting 60 operation of the cutter valve manually, this means consisting of a bell-shaped head 33 on a stem 34 passed with a close-working fit through the upper part of the coupling member 10 and provided with a knob 35 which, when struck, depresses the 65 bell-shaped head 33 and the piston 13 to effect operation of the cutter valve in the manner already described. Although the head 33 will be forced against the upper part of the coupling member 10 by the force of the discharging medium, ports 36 may be provided in the head to insure at all times free communication between the hollow cutter 16 and the outlet port 15 through the chamber 14.

Figure 2 has already been referred to in the 75 discussion of Figure 1 and no further comment

is necessary except that the provision of manually operable means on each release device permits initiation of the operation of a group of containers operatively connected from any controlled container 1, as well as from the source of control pressure 37, which is shown with a valve 38 and a valve-operating head 39.

The elements of Figures 3 and 4, which bear the same reference numerals as elements in Figure 1, are all of the same construction and have the same functions as the corresponding elements in Figure 1, so that further description of these particular elements is unnecessary. Certain elements in these figures which differ in constructional details from elements in Figure 1 having the same functions are indicated by the same reference numerals primed and double primed. These elements are, in Figure 3, the coupling member 3', the coupling member 8', the coupling member 10', and the tubular cutter 16'; while, in Figure 4, they are the coupling member 3'', the coupling member 8'', the coupling member 10'', and the tubular cutter 16''. As already pointed out, these elements serve the same functions as the corresponding elements 3, 8, 10 and 16 shown in Figures 1 and 2.

Figure 3 differs from Figure 1 in the disposition of the ports for permitting escape of the medium when accidentally released and the ports for preventing the discharge of the medium when intentionally released. The latter ports are shown at 40 and normally lie within the upper portion 41 of the coupling member 10, within which the tubular cutter 16 is conducted with a close-working fit. Upon intentional operation of the cutter valve, by admission of the actuating fluid through the port 15 into the chamber 14, the ports 40 enter into communication with the chamber 14 and thus permit discharge of the released medium through the ports 40 to the port 15. As already stated, the ports 40 are normally out of communication with the chamber 14, while ports 42 are normally in communication with the atmosphere through the annular passage 43 and passages 44, so that the medium, when accidentally released, may escape to the atmosphere. However, when the cutter valve is intentionally actuated, the ports 42 recede within the upper portion 41 of the coupling member 10, thus cutting off communication with the atmosphere. The hollow cutter 16 is shown closed at its upper end by a plug 45 and a vent 46 is shown to prevent trapping of air by the closed upper portion of the hollow cutter.

With reference to Figure 4, ports 41, normally communicating with the atmosphere through the chamber 11 and ports 25, permit the escape of the medium when accidentally released, but upon intentional operation of the cutter valve these ports recede within the contracted portion 23 of the coupling member 8. In order to prevent discharge of the medium, when accidentally released, into the chamber 14, with the consequences already fully discussed, the upper portion of the hollow cutter is arranged with a close-working fit, as at 48, on an inwardly extending projection 49 of the coupling member 10. With this particular construction there is also an additional safeguard against accidental operation upon accidental release of the medium in that the escape of the medium to the atmosphere through the ports 47 and the ports 25 creates a pressure in the chamber 11 which maintains the piston 13 in its uppermost position.

From the foregoing description it will be apparent

ent that I have made decided improvements in cutter valves of the general type referred to and it is to be understood that the present invention, while it has been described with specific reference to the accompanying drawings, is not to be limited, save as defined in the appended claims.

1. A releasing device for use in connection with a fluid container having an opening, a frangible closure member for the opening and a hollow tubular cutter adapted to penetrate said closure member constructed to provide free discharge through said closure and said cutter, comprising, a body forming a chamber, fluid operated means in the form of a piston in said chamber operatively associated with said hollow tubular cutter, a single delivery connection for admitting a fluid under pressure to the space above said piston for operating the piston, a passage extending through said piston for permitting the delivery of fluid from the container to the space above the piston when the fluid is released by operation of the hollow tubular cutter, and means normally obstructing the flow of fluid from the container through said passage to the space above the piston, said last named means being rendered ineffective upon operation of the hollow tubular cutter.

2. A releasing device for use in connection with a fluid container having an opening, a frangible closure member for the opening and a hollow tubular cutter adapted to penetrate said closure member constructed to provide free discharge through said closure and said cutter, comprising, a body forming a chamber, fluid operated means in the form of a piston in said chamber operatively associated with said hollow tubular cutter, a single delivery connection for admitting a fluid under pressure to the space above said piston for operating the piston, means for delivering fluid from the container through the hollow tubular cutter to the space above the piston when the fluid is released by operation of the hollow tubular cutter, and means normally obstructing the flow of fluid from the container to the space above the piston, said last named means being rendered ineffective upon operation of the hollow tubular cutter.

3. A releasing device for use in connection with a fluid container having an opening, a frangible closure member for the opening and a hollow tubular cutter adapted to penetrate said closure member constructed to provide free discharge through said closure and said cutter, comprising, a body forming a chamber, fluid operated means in the form of a piston in said chamber operatively associated with said hollow tubular cutter, a single delivery connection for admitting a fluid under pressure to the space above said piston for operating the piston, and means for permitting the delivery of fluid from the container through the hollow tubular cutter to the space above the piston when the fluid is released by operation of the hollow tubular cutter but normally preventing such flow, said last named means comprising a passage extending through said piston and adapted to receive one end of the hollow tubular cutter, a chamber in contiguity with the external surface of the hollow tubular cutter at a point intermediate the container and the piston chamber, a port in the walling of the hollow tubular cutter normally in communication with said intermediate chamber, a second port in the walling of the hollow tubular cutter normally out of communication with said intermediate chamber, and means normally closing off the hollow tubular

cutter at a point intermediate the first and second ports, said ports being arranged so that they are placed in communication with each other through the intermediate chamber when the hollow tubular cutter is actuated to release the fluid from the container.

4. A releasing device for use in connection with a fluid container having an opening, a frangible closure member for the opening and a hollow tubular cutter adapted to penetrate said closure member constructed to provide free discharge through said closure and said cutter, comprising, a body forming a chamber, fluid operated means in the form of a piston in said chamber operatively associated with said hollow tubular cutter, a single delivery connection for admitting a fluid under pressure to the space above said piston for operating the piston, and means for permitting the delivery of fluid from the container through the hollow tubular cutter to the space above the piston when the fluid is released by operation of the hollow tubular cutter but normally preventing such flow, said last named means comprising a passage extending through said piston and adapted to permit extension of the hollow tubular cutter therethrough to a point above the piston, means in the walling of the aforesaid body adapted to receive the extension of the hollow tubular cutter with a close-working fit, and a port in the extension of the hollow tubular cutter normally closed off by the means to receive said extension with a close-working fit but movable to a position to establish communication between the hollow tubular cutter and the space above the piston when the hollow tubular cutter is actuated to release the fluid from the container.

5. A releasing device for use in connection with a fluid container having an opening, a frangible closure member for the opening and a hollow tubular cutter adapted to penetrate said closure member constructed to provide free discharge through said closure and said cutter, comprising, a body forming a chamber, fluid operated means in the form of a piston in said chamber operatively associated with said hollow tubular cutter, a single delivery connection for admitting a fluid under pressure to the space above said piston for operating the piston, and means for permitting the delivery of fluid from the container through the hollow tubular cutter to the space above the piston when the fluid is released by operation of the hollow tubular cutter but normally preventing such flow, said last named means comprising a passage extending through said piston and adapted to receive one end of the hollow tubular cutter, and obstructing means formed on the walling of the aforesaid body in line with the passage in the piston and adapted to normally close off communication between the passage and the space above the piston, said passage being freed of said obstructing means when the hollow tubular cutter is actuated to release the fluid from the container.

6. A releasing device for use in connection with a fluid container having an opening, a frangible closure member for the opening and a hollow tubular cutter adapted to penetrate said closure member constructed to provide free discharge through said closure and said cutter, comprising, a body forming a chamber, fluid operated means in the form of a piston in said chamber operatively associated with said hollow tubular cutter, a single delivery connection for admitting a fluid under pressure to the space

- above said piston for operating the piston, a passage extending through said piston for permitting the delivery of fluid from the container to the space above the piston when the fluid is released by operation of the hollow tubular cutter, means normally obstructing the flow of fluid from the container through said passage to the space above the piston, said last named means being rendered ineffective upon operation of the hollow tubular cutter, and means normally establishing communication between the hollow tubular cutter and the atmosphere to permit escape of the fluid when released from the container upon rupture of the frangible closure member upon the development of excess pressure therein but adapted to be closed off when the hollow tubular cutter is actuated to release the fluid from the container, said last named means comprising that portion of the chamber in the aforesaid body below the aforesaid piston, and a port in the walling of the hollow tubular cutter normally in communication with the last mentioned portion of the chamber in the body but adapted to move out of communication with said portion of said chamber when the hollow tubular cutter is actuated to release the fluid from the container. 5
7. A releasing device for use in connection with a fluid container having an opening, a frangible closure member for the opening and a hollow tubular cutter adapted to penetrate said closure member constructed to provide free discharge through said closure and said cutter, comprising, a body forming a chamber, fluid operated means in the form of a piston in said chamber operatively associated with said hollow tubular cutter, a single delivery connection for admitting a fluid under pressure to the space above said piston for operating the piston, a passage extending through said piston for permitting the delivery of fluid from the container to the space above the piston when the fluid is released by operation of the hollow tubular cutter, means normally obstructing the flow of fluid from the container through said passage to the space above the piston, said last named means being rendered ineffective upon operation of the hollow tubular cutter, and means normally establishing communication between the hollow tubular cutter and the atmosphere to permit escape of the fluid when released from the container upon rupture of the frangible closure member upon the development of excess pressure therein but adapted to be closed off when the hollow tubular cutter is actuated to release the fluid from the container. 10
8. A releasing device for use in connection with a fluid container having an opening, a frangible closure member for the opening and a hollow tubular cutter adapted to penetrate said closure member constructed to provide free discharge through said closure and said cutter, comprising, a body forming a chamber, fluid operated means in the form of a piston in said chamber operatively associated with said hollow tubular cutter, a single delivery connection for admitting a fluid under pressure to the space above said piston for operating the piston, a passage extending through said piston for permitting the delivery of fluid from the container to the space above the piston when the fluid is released by operation of the penetrating means, and means normally obstructing the flow of fluid from the container to the space above the piston, said last named means being rendered ineffective upon operation of the penetrating means. 15
9. The combination with a plurality of containers of fluid under pressure, each having an opening, a closure for each opening and a fluid pressure operated fluid releasing device for opening each closure, a common fluid conducting line connected to each fluid pressure operated fluid releasing device and adapted to deliver operating fluid to each of the pressure operated fluid releasing devices and to receive fluid discharged from the plurality of containers upon operation of the respective fluid pressure operated fluid releasing devices, said fluid releasing device having a passage for establishing communication between said container and said fluid conducting line, normally positioned to coat with associated means for closing off communication between the said container and fluid conducting line whereby to prevent the passage of fluid therethrough when released from said container due to excess pressure developed in said container without operation of the fluid operated fluid releasing device of said container, the said fluid releasing device upon operation of the respective fluid pressure operated fluid releasing device by an operating fluid being moved to a position to render said coating means ineffective so that communication is established between the container and the common fluid conducting line. 20
10. A releasing device for use in connection with a fluid container having an opening, a frangible closure member for the opening and penetrating means adapted to penetrate said closure member constructed to provide free discharge through said closure, comprising, a body forming a chamber, fluid operated means in said chamber operatively associated with said penetrating means, a single delivery connection for admitting a fluid under pressure to the space above the fluid operated means to operate the fluid operated means, means for delivering fluid from the container to the space above the fluid operated means when the fluid is released by operation of the penetrating means, and means normally obstructing the flow of fluid from the container to the space above the piston, said last named means being rendered ineffective upon operation of the penetrating means. 25
